DESIGN FOR A SHOE

Samuel Huberman, New York, N. Y.

Application June 5, 1946, Serial No. 130,419

Term of patent 7 years

(Cl. D7—7)

To all whom it may concern:

Be it known that I, Samuel Huberman, a citizen of the United States, residing in New York city, in the county of Bronx and State of New York, have invented a new, original, and ornamental Design for a Shoe, of which the following is a specification, reference being had to the accompanying drawing, forming part thereof.

In the drawing:

Fig. 1 is a side elevational view of a shoe showing my new design;

Fig. 2 is a top plan view thereof.

The dominant features of the design reside in the portions shown in full lines.

I claim:

The ornamental design for a shoe, substantially as shown and described.

SAMUEL HUBERMAN.
